COOKING APPARATUS

John R. Anderson, Rochester, N. Y.

Application December 15, 1934, Serial No. 757,638

8 Claims. (Cl. 126—29)

This invention relates to cooking apparatus in the nature of a portable fire basket which may be used conveniently by campers, picnickers, and the like.

5 An object of the invention is to provide a generally improved and more satisfactory cooking apparatus of this kind.

Another object is to provide such apparatus in a form which may be readily collapsed to occupy 10 a comparatively small space when not in use.

15 Still another object is the provision of such apparatus so designed that the articles to be cooked may be placed at one side of the fire rather than above it, so that grease or other drippings from the food will not fall into the fire.

20 A further object is the provision of apparatus so constructed that the fire basket may be placed in different positions for different kinds of cooking.

To these and other ends the invention resides 25 in certain improvements and combinations of parts, all as will be hereinafter more fully described, the novel features being pointed out in the claims at the end of the specification.

25 In the drawing:

Fig. 1 is a perspective view of cooking apparatus constructed in accordance with a preferred embodiment of the invention, showing it in a position of use;

30 Fig. 2 is a fragmentary perspective view on a larger scale of one corner of the apparatus, illustrating details;

Fig. 3 is a fragmentary vertical section taken longitudinally substantially centrally through the 35 apparatus;

Fig. 4 is a perspective view of a bottom member which fits within the fire basket, and

Fig. 5 is a perspective view of the apparatus set in a different position from that shown in Fig. 1.

40 The same reference numerals throughout the several views indicate the same parts.

The apparatus comprises, in general, walls forming a hollow body capable of holding charcoal or other suitable fuel which is burned within 45 the body. There may be four such walls, preferably hingedly secured to each other to form a body which is a parallelogram in cross section, so that it may be opened up or erected to a body of rectangular cross section when in use, and may be collapsed to substantially flat condition by moving the walls relatively to each other around their pivotal joints.

50 For example, two of the walls may be in the form of plates indicated by the numerals 10, forming opposite sides of the body, while the other

two walls may be more or less open or reticulated. These other two walls may each be conveniently formed by a rectangular frame including a top bar 11, a bottom bar 12, and side bars 13 joining the top and bottom bars at each end. These 5 various bars may be separate members welded, riveted, or otherwise suitably secured to each other, or they may all be cut from a single piece of sheet metal. Suitable reticulated material or screening 14, preferably a wire screen of a kind 10 not seriously warped by heat, is secured in any suitable manner to each frame so as to extend across the rectangular space enclosed by the members 11, 12, and 13. If the frame is made of sheet metal, the outer edge of each of the 15 bars 11, 12, and 13 may conveniently be doubled back upon itself to form a channel for receiving an edge of the screen material 14 to hold it in place, as shown in Fig. 2.

Each of these frames is pivoted or hinged at 20 each end to one edge of one of the plates 10. Each plate 10 may be cut away at its upper and lower corners as indicated at 16 in Figs. 1 and 2, and intermediate these corners the plate may have its edge doubled back upon itself or rolled 25 so as to hold a pin 17 which extends upwardly into a hole in the bar 11 formed by doubling back a projecting end of the bar 11 upon itself, and downwardly into a similar hole in the end of the lower bar 12. A similar construction is used at 30 each corner, so that the four walls are hingedly connected to each other to form a parallelogram, and may be erected into the rectangular shape shown in Figs. 1 and 5, or may be collapsed to a much thinner structure in which the two sides 35 having the screens 14 in them lie much closer to each other.

At the bottom of each plate 10 is a flange 19 (see Fig. 3) projecting inwardly or toward the corresponding flange on the opposite plate 10. 40 These two flanges 19 form supports for a bottom member 20 which may be in the form of a flat plate having upstanding side flanges 21 which lie substantially against the inner surfaces of the bottom rails 12 when the body is in normal erected 45 position as in Fig. 1. The bottom 20 simply rests loosely on the flanges 19, and serves not only to support charcoal or other suitable fuel placed within the fire basket, but also to hold the basket in erected rectangular position and to prevent 50 it from collapsing. When the bottom member is removed, the fire basket may be collapsed by folding the walls relatively to each other about their hinged joints at the corners of the basket.

On each plate 10 is suitable means for attach- 55

ing a detachable supporting member or leg. This attaching means preferably is of a form which permits the supporting member or leg to be attached in more than one position, so that the fire basket may be set in more than one position. For example, the attaching means may comprise a plate 25, riveted, spot welded or otherwise secured to the member 10, which plate 25 has four bent-over ears or lugs 26 substantially around four sides of a square, as plainly shown in Figs. 1 and 5. These lugs 26 have a little space between them at the corners of the square, as shown. The leg member comprises a wire rod or the like bent to provide a substantially U-shaped portion 28 near its middle, of the proper size to fit between any two opposite lugs 26, and having two projecting ends or legs 29, as shown.

To attach the leg member, the top or horizontal part of the U-shaped portion may be inserted just above the bottom one of the lugs 26, where the rounded corners of this U-shaped member will clear the lugs. The leg member is then moved upwardly to the position shown in Fig. 1, so that the vertical parallel portions of the U-shaped part slide upwardly within the two side lugs 26, until the top or horizontal member comes in contact with the upper lug 26 which holds it against further upward movement. The leg member may be detached by a reverse operation.

When the leg member is attached in proper position, the leg portions 29 thereof extend obliquely outwardly away from each other, and also preferably incline away from the plane of the member 10, as will be seen from Fig. 3. With such a leg member attached at each of two opposite sides of the fire basket (that is, to each of the plates 10) it will be seen that the fire basket is adequately supported in a steady manner, and its bottom is held up off of the ground so that the heat of the fire will not accidentally set fire to dry leaves or other inflammable material which may be on the ground.

Adjustable bracket means is provided for supporting the food to be cooked at one side of the fire basket. The bars 11 may be provided with transverse holes 35 aligned with each other when the basket is in normal erected position, and a bracket member 36, formed of a length of wire or rod bent into generally U-shaped form, may be inserted through these aligned holes 35 as shown in Fig. 1 and may be adjusted to various positions by moving it longitudinally through the holes. A cross piece 37, welded or otherwise suitably secured across the member 36 near the closed end thereof, serves as a stop member to limit the movement of the member 36 in one direction through the holes 35, to a position in which the closed end of the member 36 projects from the plane of the side of the fire basket by an amount substantially equal to the projection from such plane of the adjacent ends of the legs 29 when they are in the position shown in Fig. 1. Thus, without shifting the position of the legs, the basket may, if desired, be tipped on its side and be supported in substantially horizontal condition, resting upon the closed end of the member 36 and on one leg 29 of each of the pairs of legs.

When steaks or other articles are to be broiled, they may be placed within the usual conventional wire broiling frame indicated in general at 40, which may be hung on the projecting ends of the bracket member 36 when the fire basket is in upright position, all as shown in Fig. 1. During the broiling operation, the broiler frame 40 may be readily moved closely to or further away from

the fire basket, as required, either by grasping the frame 40 itself and moving it along the bracket member 36, or by moving the bracket member 36, by grasping its opposite end, in one direction or another through the holes 35. When the food is held in this position, it will be seen that it receives the full heat of the fire through the reticulated side of the fire basket which is next to the food, yet it is not directly over the fire so that it is relatively out of the way of smoke from the fire. Also grease and other drippings from the food fall downwardly at the side of the fire basket and do not fall into the fire itself, which might cause the fire to blaze up and produce excessive smoke. While the apparatus is being used in broiling in this manner, a coffee pot, frying pan, or other desired utensil may be set on top of the fire basket, merely resting on the upper edges of the side walls thereof.

Because the holding flanges 26 for the detachable leg means are symmetrical and are arranged in substantially square formation, it follows that the legs may be inserted in these holding flanges in various different positions and need not always be inserted in the same position. Hence, if for any reason it is desired to place the fire basket with its reticulated sides horizontal instead of vertical, the legs may be inserted into the square formed by the flanges 26 from a different side, with a result that the fire basket will be supported in a substantially horizontal position, as shown in Fig. 5. In this position, a frying pan or other utensil may rest on top of the upper reticulated side of the fire basket and receive full heat therefrom throughout substantially its entire area. This position of the fire basket is useful when boiling operations are desired, and obviously it could also be used for broiling, although it is usually preferred to broil in the vertical position shown in Fig. 1.

When the cooking operation is completed, and the parts have cooled off, the bracket member 36 is removed by pulling it out of the holes 35, the legs 29 are taken off, and the bottom member 20 is removed, which may be done by raising one end of it by a finger inserted from beneath, until the opposite end drops off of its supporting flange 19. With the bottom member 20 removed, the four walls of the fire basket may then be collapsed to a substantially flat position, but with enough space left between the two reticulated walls so that the bottom 20, the two leg members, and the bracket member 36 may all be inserted inside the collapsed body to form a compact, unitary package which may be easily transported.

I claim:

1. A portable fire basket comprising two substantially rectangular frames, an open mesh screen held in each frame, two plates, hinge connections joining the frames and plates to each other to form a collapsible fuel holding body having a substantially parallelogram-shaped cross section, supporting legs, and means for detachably fastening said legs to said plates in either one of two different positions, in one of which said legs are effective to support one of said screen substantially vertically, and in the other of which said legs are effective to support said one of said screens substantially horizontally.

2. Cooking apparatus comprising walls forming a hollow body for holding fuel, detachable supporting legs, and means for attaching said legs to said body in either of two different posi-

tions at a substantial angle to each other so that when said legs are in one of said two positions said body may be supported with one of its walls substantially horizontal for use in one manner, and when said legs are in the other of said positions, said body may be supported with said one of its walls substantially vertical for use in a different manner.

3. Cooking apparatus comprising a wall, means on said wall forming ears substantially on four sides of a square, and detachable supporting means including a portion insertable between any two opposite ears to be held thereby, so that said supporting means may be attached to said wall in a plurality of different positions for supporting said wall in a plurality of different positions.

4. Cooking apparatus comprising walls forming a hollow body for holding fuel, means on one of said walls forming ears projecting outwardly and bent over and extending toward each other substantially along four sides of a square, and a detachable supporting member formed of a rod bent to provide a U-shaped portion insertable between the ears on any two opposite sides of said square to be held thereby, so that said supporting member may be attached to said wall in a plurality of different positions to support said fuel holding body in different positions for use in different ways.

5. Cooking apparatus comprising walls forming a hollow body for holding fuel, one of said walls having a plurality of openings therein, leg means extending downwardly and outwardly from said body and terminating in ends offset laterally from said body, said leg means serving to hold said body in an upright position with said one wall substantially vertical so that articles placed beside said wall may receive heat therethrough, and means projecting laterally from said body from a point adjacent that part of said body which is the top thereof when said body is in said upright position, said laterally projecting means and said laterally offset leg means serving as supporting members for holding said body in a position turned substantially 90° from said upright position, with said one of said walls arranged substantially horizontally so that articles to be heated may rest thereon.

6. Cooking apparatus comprising walls forming a fuel holding body of substantially rectangular shape when in normal position of use, said walls on two opposite sides of said body having a plurality of openings therein, leg means associated with certain of said walls for supporting said body in an upright position with said two walls substantially vertical, and bracket

means supported by certain of said walls and extending laterally to provide a support from which articles may be hung in position adjacent one of said two walls having openings, to receive heat through said openings, said bracket means 5 and said leg means both extending laterally to points offset by substantially equal distances from the plane of one of said two walls having openings, so that said body may be turned on its side and supported by said bracket means and said 10 leg means and with said two walls arranged substantially horizontally so that one of them provides a support on which articles to be heated may be placed.

7. Cooking apparatus comprising walls forming a hollow body for holding fuel, one of said walls being approximately flat and of substantial area, and leg means attached to said body and projecting therefrom to spaced points lying approximately in a plane spaced from said body 20 and parallel to said one of said walls and defining a stable supporting base approximately in said plane, said leg means projecting from said body also to spaced points lying approximately in a plane spaced from said body and perpendicular 25 to said one of said walls and defining a stable supporting base approximately in said last named plane, so that either of said two supporting bases defined by said legs may be placed upon the ground to support said hollow body for use in 30 either of two different positions both spaced substantially above the ground, in one of which positions said one of said walls is approximately parallel with the ground so that articles to be heated may rest thereon, and in the other of 35 which positions said one of said walls is approximately perpendicular to the ground so that articles to be heated may be hung along side of said one of said walls.

8. Cooking apparatus comprising walls forming a hollow body for holding fuel, means on said body forming ears projecting outwardly and bent over and extending toward each other substantially along four sides of a square, and a detachable supporting member including a portion 45 insertable between the ears on any two opposite sides of said square, so that said supporting member may be attached to said body in either of two positions substantially at a right angle to each other, in one of which positions one wall 50 of said body may be supported substantially vertically so that articles to be heated may be hung along side of said wall, and in the other of which positions said one wall of said body may be supported substantially horizontally so that articles 55 to be heated may rest on top of said one wall.

JOHN R. ANDERSON.
